UNITED STATES PATENT OFFICE

2,432,498

KEY INDICATOR

Samuel Bloomfield, Wichita, Kans., assignor to
C. Earl Hovey, trustee, Kansas City, Mo.

Application August 24, 1945, Serial No. 612,427

7 Claims. (Cl. 40—2)

1

This invention relates to a new article of manufacture in the nature of an attachable indicator for keys or similar elements where it is desired to provide means for identifying the same through the sense of touch.

The primary aim of the invention is to provide a key indicator constructed for easy attachment to the handle portion of a lock key as it is hung upon a key ring or within a key case to the end that the user thereof may identify any of the keys of the collection when it becomes necessary to select one for use in a lock and where it is impossible to view the key for visual recognition.

One of the important objects of this invention is to provide a key indicator that is positive in its gripping action after application to the key; that is small, unobtrusive and does not hinder the free use of the key to which it is attached; that is attachable without the use of special tools or equipment and that is of such a size and contour as to permit a number thereof to be applied to keys for purpose of further identifying the keys of a group with respect to each other.

Other aims and important objects of the invention will appear during the course of the following specification referring to the accompanying drawing, wherein:

Fig. 1 is an edge elevational view of a door key showing a key indicator made in accordance with the present invention affixed thereto for purpose of identifying the same.

Fig. 2 is a side elevational view of the key and indicator assembly shown in Fig. 1.

Fig. 3 is an enlarged side elevational view of the key indicator per se showing the same entirely removed from its operative association with a key.

Fig. 4 is an end elevational view of the key indicator.

Fig. 5 is a side elevational view thereof.

Fig. 6 is a side elevational view of a key indicator made in accordance with a modified form of the invention, and

Fig. 7 is a side elevational view of the key indicator shown in Fig. 6.

It has heretofore been customary to identify keys by placing numerals thereon or by attaching tags with designating indicia that would teach the user of several keys the particular lock which the keys fit. Objections are present when following the customary course as just set down or when otherwise making effort to identify keys particularly because the individual keys are not visible in the dark and the keys cannot be distinguished through the sense of touch. It is also inconvenient to prepare and condition the keys

2

with numerals or tags and therefore, the keys carried by the ordinary person are left without means of indication.

Because the indicator made pursuant to this invention may be quickly attached and further because a number of the relatively small indicators may be affixed to a key, the commercialization of the invention has met with favor.

In the form of the invention shown in Figs. 1 to 5 inclusive, a conventional door key 10 is equipped with an indicator broadly designated by the numeral 12 and comprising a hollow case of drawn metal to present a head 14 and a pair of arms 16 between which arms the key is positioned when the indicator is moved to the operative location. These arms 16 are resilient, and during the formation of the indicator the distance between said arms 16 is made slightly less than the thickness of the conventional key. A spacer 18 in the form of a sphere or ball-bearing having a diameter substantially the same or minutely greater than the thickness of the material from which the keys are made is interposed between arms 16 to facilitate the introduction of key 10 therebetween. When such introduction is made and during the application of the indicator to key 10, spacer 18 is rolled into hollow head 14 and there confined. Under some conditions the spacer 18 may be moved from between its position between arms 16 and thrown away. Under any consideration the spacer must be capable of holding arms 16 far enough apart to permit the convenient and easy assembly of key and indicator as just above set down.

In the modified form of the invention illustrated in Figs. 6 and 7, the indicator case 50 has a hollow head 52 and a pair of substantially parallel opposed arms 54 held apart by a spacer 56 which, in this particular instance, is struck from one of arms 54 and bent inwardly to a point where the said arms are held apart a distance slightly greater than the thickness of the material from which the key is made. When the key is introduced between arms 54, spacer 56 is moved back toward its original position in a plane with one of arms 54 and there remains so long as the indicator is in use. In some instances, keys 10 have a marginal bead 58 thereon and under that condition the free end of spacer 56 bears against the bead 58 as illustrated in dotted lines of Fig. 6. A number of indicators may be applied at the periphery of the key handle and since the bulk of the indicator is not great enough to effect handling of the key nor present objections when

carrying the same, the indicator is a highly desirable article of manufacture.

The indicator is sold in quantities and applied by the user to the keys in any number needed to fully indicate to him the locks to which the individual keys apply.

Having thus described my invention, what I claim as new and desire to secure by Letters Patent is:

1. A key indicator comprising a body provided with opposed spaced apart parts for gripping the key to which it is applied, the space between said parts being less than the thickness of the key; and a displaceable member between the opposed parts for holding the latter in spaced relation greater than the thickness of said key before the key is introduced therebetween, said body having a tubular portion extending beyond the edge of the key when the indicator is in operative position.

2. A key indicator comprising a body provided with opposed spaced apart, resilient parts for gripping the key to which it is applied, the space between said parts being less than the thickness of the key; and a displaceable member between the opposed parts for holding the latter in spaced relation greater than the thickness of said key before the key is introduced therebetween, said body having a tubular portion extending beyond the edge of the key when the indicator is in operative position, said member being shiftable by the key as it is moved between the parts.

3. A key indicator comprising a body provided with opposed spaced apart, resilient parts for gripping the key to which it is applied, the space between said parts being less than the thickness of the key; and a displaceable member between the opposed parts for holding the latter in spaced relation greater than the thickness of said key before the key is introduced therebetween, said body having a tubular portion extending beyond the edge of the key when the indicator is in operative position, said member being shiftable by the key as it is moved between the parts, the space between said parts where the member is absent being slightly less than the thickness of the key with which the indicator is to be used.

4. A key indicator comprising a body provided with opposed spaced apart, resilient parts for gripping the key to which it is applied, the space between said parts being less than the thickness of the key; and a displaceable member between the opposed parts for holding the latter in spaced relation greater than the thickness of said key before the key is introduced therebetween, said body having a tubular portion extending beyond the edge of the key when the indicator is in operative position, said member being shiftable by the key as it is moved between the parts, said displaceable member being a spherical unit.

5. A key indicator comprising a body provided with opposed spaced apart, resilient parts for gripping the key to which it is applied, the space

between said parts being less than the thickness of the key; and a displaceable member between the opposed parts for holding the latter in spaced relation greater than the thickness of said key before the key is introduced therebetween, said body having a tubular portion extending beyond the edge of the key when the indicator is in operative position, said member being shiftable by the key as it is moved between the parts, said displaceable member being a spherical unit, said body having a cavity provided therein in communication with the space between said parts to receive the spherical unit as the same is moved from a position between the parts by the key to which the indicator is being applied.

6. A key indicator comprising a body provided with opposed spaced apart, resilient parts for gripping the key to which it is applied, the space between said parts being less than the thickness of the key; and a displaceable member between the opposed parts for holding the latter in spaced relation greater than the thickness of said key before the key is introduced therebetween, said body having a tubular portion extending beyond the edge of the key when the indicator is in operative position, said member being shiftable by the key as it is moved between the parts, said displaceable member being an ear struck from one of the said parts and having its free end against the other part before the key is introduced between the parts, said ear being bendable and having said free end against one face of the key to exert gripping pressure thereagainst when the key is between the parts.

7. As a new article of manufacture, an indicator adapted for attachment to the thing to be identified, comprising a body having a hollow head and a pair of opposed spaced apart, resilient arms for straddling the thing to which the body is attached, the space between said parts being less than the thickness of said thing; and an element for spacing the arms a distance greater than the thickness of the thing to be identified, formed to be shifted from its operative position to an inoperative position as the body is being attached, said head extending beyond the edge of the said thing for identifying the same when the indicator is in operative position.
